DISPENSING DEVICE

Samuel Shapiro, New York, N. Y., assignor to
Olga Liben, Bronx, N. Y.

Application June 9, 1930, Serial No. 459,920

30 Claims. (Cl. 312—57)

My invention relates to devices for the dispensing or withdrawing of articles, one by one, from a suitable receptacle or magazine which may at intervals be charged or supplied with a large number of such articles.

In accordance with my invention in its preferred form a supply of articles to be dispensed, for example, paper napkins, are placed in superposed relation upon a magazine follower or other feeding device and a movable member is brought into engagement with the uppermost article, pressing upon and moving along it, whereby one end of the article is caused to separate itself from the article beneath it to a sufficient extent to permit another movable member to engage such end and move it into a position where it may be readily grasped by the user and withdrawn from the machine.

In the preferred form of the invention, the feeding device is a movable follower which exerts spring pressure upon a supply of articles carried thereby during at least a part of the dispensing operation and the invention contemplates the provision of means for relieving the uppermost article of such pressure at the time when it is to be withdrawn so that its withdrawal will be facilitated and the possibility of its causing any displacement of other articles is avoided.

One form or species of dispensing device embodying the invention is disclosed and claimed in my application Serial No. 331,074, filed January 8, 1929. Another species is disclosed and claimed in the present application which is, in part, a continuation of said application. It is applicant's intention to claim the invention generically in the present application.

This application is also a continuation in part of my application Serial No. 355,065 filed April 15, 1929.

Reference is hereby made to the accompanying drawings, of which

Figure 1 is a side elevation of a dispensing device constructed in accordance with my invention, the enclosing casing being removed;

Fig. 2 is a section on line 2—2 of Fig. 1;

Fig. 3 is a section on line 3—3 of Fig. 4;

Fig. 4 is a section on line 4—4 of Fig. 3, showing in full lines the dispensing mechanism in normal position and in dotted lines the position assumed when the hand lever is depressed.

Fig. 5 is a view similar to Fig. 4 with hand lever in depressed position and the dispensing mechanism in the position corresponding thereto, and showing in dotted lines the positions to be assumed by the article being dispensed and the

part by which it is moved as the hand lever returns to normal position. It also shows the cover plate in position.

Fig. 6 is a perspective view of a casing with cover plate for enclosing duplicate dispensing devices facing in opposite directions, with open door for permitting access to one of such devices.

Fig. 7 is a perspective view of the follower;

Fig. 8 is a plan view on a reduced scale illustrating the manner in which a napkin may be folded in order to be dispensed by the device and

Fig. 9 is an enlarged detail view illustrating the action of the dispensing mechanism upon a folded napkin.

Referring to Figs. 1, 2 and 6, the device shown comprises a base 1, and a casing or body 2, preferably of metal, within which the working parts are housed. A door 3, preferably also of metal, is hinged to the casing and is provided with locking means 3^a for securing same in closed position. Within the casing 2 and secured thereto and to the base 1 is a metal supporting frame. This frame comprises metal sheets 4 which form the side walls of the magazine within which the follower travels. The plates 4 are bent to form vertical channels or guides 5. The plates 4 are provided along their rear edges with integral flanges 6 and are secured together by a vertical metal plate 7 and corner angle strips 8, metal screws 11 passing through said strips, plate and flanges, as shown in Fig. 3.

The forward edges of the side plates 4 are secured together in a manner similar to the rear edges, with the exception that the vertical plate 7' and the corner angle strips 8' which correspond to the plate 7 and strips 8 extend only a short distance in a vertical direction, as shown in Fig. 1, so as to permit loading of the follower.

There is a pair of side plates 9 which are secured at their ends by screws 10 to the respective angle strips 8 and 8'. These plates support the dispensing mechanism.

The rear wall of the magazine is a vertical sheet 13 having integral flanges 14 which are secured to the walls 4 by screws 15. This wall has also a top flange 16.

The front wall of the magazine is formed in part by a vertical plate 17 which extends only a short distance below the top of the magazine as shown in Figs. 4 and 5. The space below this plate is normally closed by the panel 18 of the door 3, but when the door is opened, as shown in Fig. 6, the magazine is open throughout substantially its entire height and width to permit the

easy loading of the follower with bundles of napkins.

The top wall of the magazine is a horizontal plate 19 having integral flanges 20 secured to the side plates 9 by screws 21.

The follower is shown in detail in Fig. 7 and comprises a sheet metal plate 22 bent into the form of an inverted U. The vertical walls 23 of the follower are provided with pairs of upper and lower guide rolls 24. These rolls may be conveniently supported by cutting and bending the metal of said walls to form integral ears or lugs 25 which support the horizontal pins 26 upon which the rollers 24 are journaled. Each roller 15 extends into the opening in the wall 23 which is formed by the bending of said tongues. A single tongue instead of a pair of tongues may be used for supporting the roller, if desired.

One of the side walls 23 of the follower is provided with a toothed detent 27 which is rigid therewith and will be referred to later. Each side wall 23 has a stud 28 rigid therewith.

In assembling the device the follower is placed within the magazine with the outer edges of the rollers 24 occupying the channels 5. The studs 28 and the base of the detent 27 pass respectively through the vertical grooves 29 of the magazine walls 4, so as to permit vertical movement of the follower. The detent base and the stud which is 30 on the opposite wall of the follower are fitted to said groove so as to aid in guiding the follower, said stud having an enlargement or roller 28' for this purpose.

The follower is normally urged in an upward direction by means of coil springs 30 and flexible tension members 31. The latter may be cords of any suitable material, one extremity of the tension member is secured to a stud 28 of the follower and extends thence over a sheave or pulley 32 rotatably mounted on the wall 4, thence around a pulley 33 rotatably in the floating frame 34, thence over a pulley 35 rotatably mounted on the wall 4, thence to the frame 34. One end of each of the coil springs 30 is attached to a frame 34 and the other end to a lug 36 rigid with a wall 4. By means of this arrangement a longitudinal contraction of the springs of one inch causes a three inch movement of the follower.

Any desired ratio of spring and follower movement may be obtained by varying the number of fixed and floating pulleys. In practice the arrangement shown for producing a 3 to 1 movement causes a substantial balancing of spring tension and follower weight. When the follower is in its lowest position and fully loaded with articles to be dispensed its weight is a maximum. At this time the spring 30 is at its greatest elongation and is exerting maximum tension on the cord 31. Such tension is sufficient to elevate the follower so as to cause the uppermost article to be pressed against the top plate 19 of the magazine with a moderate pressure.

As the articles are removed through the dispensing outlet, the follower is caused to rise. Its weight decreases at a uniform rate and the tension of the springs decreases at substantially the same rate, the effect of which is to cause the uppermost article to be pressed against the plate 19 with substantially uniform pressure, irrespective of the number of articles which are carried by the follower.

The means for separating one end or extremity of the uppermost article from those beneath it upon the follower and for thereupon moving such end so as to increase its separation and enable it

to be readily grasped by the user is broadly new, and while adapted to operate upon articles of various kinds, has been very successfully applied to the dispensing of paper napkins folded in a particular manner, as will be described.

Referring to Fig. 8, a paper napkin *a* is preferably folded in opposite directions along the lines *b* and *c*, thus producing a zig zag formation. It is then folded along the line *d*. Various other types of fold may be used, as long as the final fold is along a line substantially equidistant from the ends of the napkins, and preferably at right angles to the longest dimension of the resultant article.

The napkins as thus folded are superposed to form a pile or bundle and loaded into the magazine in such manner that the line of fold of each napkin is at the left, Figs. 4 and 5.

The dispensing mechanism, shown in detail in Figs. 1 to 5, comprises a pair of levers 41 which are pivoted by screws 42 to opposite side plates 9 of the frame. These levers are united by a cross bar 44 integral therewith and having angle plates 45 to which is secured suitable hand operating means, as for example an arm 46 which passes through a slot 47 in the cover 12 and is provided with a button 48. Each of the levers 41 is provided with two arms 49 and 55, as shown. The arm 49 is substantially horizontal and is provided at its extremity with a pin 50 which engages a slot 51 formed in a plate 52. This plate is pivotally mounted on the side plate 9 by means of a screw 53. There are two of the plates 52, one mounted on each of the side plates 9 of the frame and such plates are united by a rod 67, one end of which is secured to each of said plates.

Upon the rod 67 is a sheet metal guard 38 which is held against turning thereon by engagement of an ear 39 with an aperture 37 in one of the plates 52, see Figs. 3 and 4. In its normal position the guard 38 substantially closes the opening 76^a in the cover plate 12, see Fig. 4.

Each of the plates 52 is provided with a pin 60 which engages a slot 61 formed in a plate 62. The plate 62 is pivotally mounted on side plate 9 by a screw 63 upon which it turns. The two plates 62 are united by a rod 54. The cross section of this rod is preferably such as to form a sharp edge 54^a (Fig. 9) for engaging the surface of the article to be dispensed.

The arm 55 of one of the levers 41 extends in a downward direction from the pivots 42 and at its lower end is provided with a pin 56 which engages a slot 57 in a lever arm 58. The arm 58 is pivoted at 59 to the plate 64 which is secured by screws 65' to side plate 9.

The function of the lever arm 58 is the actuation of the follower 22 through the following elements. A link 65 is pivoted at one end to arm 58 by a pin 66, the opposite end of said link being pivotally connected to a vertical bar 67' by a pin 68. The bar 67 extends practically the full height of the magazine frame and is provided with upper and lower slots 69 which cooperate with fixed pins 70 carried by plates 70^a secured to the side wall plate 4.

One edge of the bar 67 is formed with ratchet teeth 71 in such position that as the bar is moved laterally said teeth will engage similar teeth on detent 27 carried by the follower 22.

The levers 41 are normally held in the position shown in Figures 1 and 4 by coil springs 74. One end of each spring is formed as a hook which passes through a hole in one of the arms 55 and the other end of said spring is secured in a similar manner to the side plate 9, the body of the

spring being disposed in an opening 75 formed therein. The tension of these springs is sufficient to move all parts from dotted to full line positions, Fig. 4 thereby depressing the follower.

5 The cover 12 is removably mounted on the casing 2. This cover is provided with a transverse slot 76 through which the dispensed articles may be withdrawn. In order that the same may be readily grasped, a trough-like depression 77 is formed in the cover, which depression is braced by a depending flange 78. The trough 77 forms an opening 76^a in the cover which is normally closed by the guard 38.

The operation of the device is as follows:

15 Assuming the magazine to be empty, the door 3 will be opened and the follower 22 depressed by hand, first releasing the same from the bar 67' by depressing the hand lever 46. Since the magazine is ordinarily of considerable height, a large 20 number of articles to be dispensed, for example paper napkins, may be placed upon the follower, completely filling the magazine. The width of the door 3 is substantially the same as or greater than the distance between the side walls 4, 4' of 25 the magazine so that the napkins may be readily inserted. The door 3 is then closed and secured.

In order to obtain one of the napkins or other articles, the user depresses the lever 46 and causes the dispensing mechanism to move from 30 the full line position of Fig. 4 to that shown in dotted lines. Such movement by reason of the action of the lever arm 55 causes the arm 58 to move upward, thereby actuating the bar 67' and causing it to move upward and away from 35 the detent 27 of the follower. The ratchet teeth 71 of the bar 67' are withdrawn from engagement with the teeth of the detent 27, and thereby free the follower and allow the springs 30 to cause the follower to move upward to the limiting position which is determined by the top 40 napkins coming in contact with the plate 19, Figs. 4 and 5.

Simultaneously with the action which has just been described, the arms 49 of levers 41 cause 45 the plates 52 to be moved from the full line to dotted line position, Fig. 4, so that the uppermost napkins can readily move past the guard 38. The movement of the plate 52 by reason of engagement of pin 60 with slot 61 causes the arms 50 62 and rod 54 to move from full to dotted line position Fig. 4. Since the follower 22 by reason of the resiliency of the coil springs 30 is holding the uppermost napkin in firm contact with the said rod 54, the effect of the movement of said rod is to cause the upper layer *e* of the napkin 55 to exert a pull upon the lower layer *f*, whereby the end of the napkin at the line of fold is raised and separated from those below it as shown in Figs. 5 and 9. This movement of the upper napkin is 60 sufficient in extent to bring the free end above the guard 38. The flange 16 of the plate 13 is to prevent the napkins below the uppermost one from being elevated, or in case one or more of them should rise above said flange they will be held 65 against any lengthwise movement by the end wall parts 13^a which extend above the level of the flange 16, and will be brought below the said flange when the follower is depressed by the bar 67' as will be described.

70 With the parts in the position of Fig. 5, the user thereupon releases the button 48 and lever 46, and the coil springs 74 cause the parts to move from dotted to full line position of Fig. 4. These movements, being exactly the reverse of 75 those which were caused by the depression of

lever 46, accomplished the following results, namely, bar 67' is caused to move laterally and downwardly until the teeth 71 engage the teeth of the detent 27 and the bar 67' then moves straight down, thereby depressing the follower a 80 distance substantially equal to the vertical portion of the slots 69. This causes the uppermost napkin to be relieved of pressure from below, so that it may be more readily withdrawn and so 85 that when it is being withdrawn there will be no tendency for it to cause the napkin immediately beneath it to be displaced.

Simultaneously with the action just described, the rod 54 and guard 38 move from the full line to dotted line position Fig. 5. The effect of the 90 movement of the guard is to move the end of the uppermost napkin from full to dotted line position. It should be noted that the end of the napkin is now in the slot 76 of the cover and that by reason of the trough 77 it is very easy to grasp 95 such end of the napkin between the thumb and finger and withdraw the napkin from the device without displacing or disturbing in any way the articles which remain.

The device cannot be rendered inoperative by 100 any jamming of articles therein due to operating the lever 46 again without removing the article which has been previously brought into position for withdrawal, for the reason that such second or repeated operation of the lever 46 will have no 105 effect upon the articles in the device, since the cross rod 54 engages only the uppermost article. It is impossible for the apparatus to cause the elevation of any article below the uppermost one sufficiently to enable it to be engaged by the 110 guard 38. In case the lever 46 is depressed without removal of the article previously brought into position for withdrawal, the various parts will simply move idly from full line to the dotted line position of Fig. 4 and return without affecting any 115 of the articles, and not until the uppermost article has been pulled out of the dispensing device by the user does it become possible to separate the next article from those beneath it in the magazine. 120

I claim:

1. In a dispensing device, a follower for feeding a stack of folded, flexible sheets each having a transverse line of fold forming the forward end thereof, means engagable with and movable 125 rearwardly over the outermost folded sheet for causing the forward portion thereof to flex away from the stack, and means movable towards and into engagement with said flexed portion to increase the amount of flexure thereof. 130

2. In a dispensing device, a movable follower adapted to support a stack of folded sheets of flexible material each having a transverse line of fold forming the forward end thereof, and means arranged to move into engagement with the face 135 of the outermost article feed towards it by said follower and rearwardly along said face while pressing thereon, whereby the portion of the article contacted by said means is caused to flex away from the stack. 140

3. A dispensing device as defined in claim 2 including means movable rearwardly towards and into contact with the flexed portion of the article for moving the same into position to be grasped.

4. In a dispensing device, a follower, means for 145 moving said follower, means movable toward and along an article fed toward it by said follower, whereby the article contacted by said means is caused to separate from those between it and said follower, and means actuated in coordination 150

- with said first named means for engaging and depressing the follower to relieve the separated article from the pressure thereof.
5. In a dispensing device, a follower for feeding a supply of articles, means for causing one end of the outermost article to separate from the others, means for engaging such separated end and moving it into a position to be grasped, and means actuated in coordination with said first named means for engaging and depressing the follower.
6. In a dispensing device, a follower, a movable member for engaging and moving by flexure one extremity of the outermost of a series of articles fed thereby, means for further flexing said extremity, means acting directly upon the follower to cause its retraction, and a unitary device for operating said member and both of said means.
7. In a dispensing device, a follower for feeding a supply of articles, means for flexing one extremity of one of the articles to cause it to separate from such supply, and means operated with said first named means and acting after such separation directly upon the follower to cause its retraction.
8. In a dispensing device, a follower having means for feeding a supply of articles, means for flexing one extremity of one of the articles to cause it to separate from such supply, means acting directly upon the follower to cause its retraction against the action of said feeding means, and a unitary device for operating both of said means.
9. In a dispensing device, a follower for feeding a supply of articles, means for separating one of the articles from such supply, and an elongated, spring actuated, longitudinally movable rod acting after such separation directly upon the follower to cause its retraction.
10. In a dispensing device, two members pivoted on independent parallel axes, and united by a pin and slot connection, and unitary means for causing one of said members to press upon an article to separate it from the other articles to be dispensed, and for causing the other member to thereafter move towards and engage and move said article.
11. In a dispensing device, a spring actuated follower for feeding a supply of articles to be dispensed, means for separating the outermost article from the others, and an elongated, longitudinally movable member actuated in coordination with said separating means for moving the follower away from said article during the dispensing thereof.
12. In a dispensing device, a spring actuated follower for feeding a supply of articles to be dispensed, means above the follower in contact with the supply of articles held thereagainst by the follower a detent carried by the follower, a rod having a row of teeth adapted to engage said detent, and means for actuating said rod to cause it to move said follower against the action of said spring away from said first named means to release the articles.
13. In a dispensing device, a spring actuated follower for feeding a supply of articles to be dispensed, means for separating the outermost article from the others, a bar extending parallel to the path of movement of said follower for moving it against the action of said spring to release the articles, and unitary means for actuating said separating means and said bar.
14. In a dispensing device, a movable follower for a stack of folded, flexible sheets each having a transverse line of fold forming the forward end thereof, means movable towards and rearwardly along in pressing engagement with the surface of the outermost article inwardly from one extremity thereof to cause said extremity to flex to separate the same from the stack, and means movable towards the flexed extremity of the article to move the same to increase the separation.
15. In a dispensing device, a spring actuated follower for a stack of folded, flexible sheets each having a transverse line of fold forming the forward end thereof, a pivoted member adapted to swing rearwardly into engagement with the surface of the outermost article inwardly of the forward extremity thereof and exert a pressure thereon in a direction away from said extremity to cause the same to flex outwardly away from the stack, and means actuated to engage the flexed extremity of the article and move the same to further increase the extent of separation.
16. In a dispensing device, a spring actuated follower for a stack of folded, flexible sheets each having a transverse line of fold forming the forward end thereof, a wall at the opposite side of the stack overlying a portion thereof, means movable in a direction towards said wall into engagement with the surface of the exposed portion of the outermost article inwardly of the free extremity thereof to exert a pressure on said article in a direction away from said extremity to cause the same to flex outwardly away from the stack, and means actuated to engage the flexed extremity of the article to further flex the same.
17. In a dispensing device, a magazine for a stack of flexible articles including a spring actuated follower, means actuated to cause separation of one extremity of the outermost article from the stack, and means coordinated with said separating means to retract said follower after the separating operation to allow removal of the separated article.
18. In a dispensing device, a magazine having a follower for supporting a stack of flexible articles, spring means for moving said follower upwardly, a wall portion overlying a portion of the stack at the opposite end and receiving the thrust of said follower, means actuated to engage the surface of the exposed portion of the outermost articles inwardly of the extremity thereof to cause the flexure thereof, means actuated to further flex the exposed extremity of said outermost article, means for retracting the follower to release the flexed article, and unitary means for actuating said flexing and retracting means.
19. In a dispensing device, a movable follower for a stack of folded, flexible sheets each having a transverse line of fold forming the forward end thereof, a wall portion engaging a portion of the stack at the opposite end, a swinging member adapted to engage the surface of the outermost article inwardly of the free extremity thereof and exert a rearward pressing action thereon to effect partial flexure of the free extremity away from the stack, and swinging means coming into action after the initial flexing and engaging the flexed portion to move the same substantially into a position at right angles to the body thereof.
20. In a dispensing device, a movable follower for a stack of folded, flexible sheets each having a transverse line of fold forming the forward end thereof, a wall portion engaging a portion of the stack at the opposite end, a swinging member adapted to engage the surface of the outermost

- article inwardly of the extremity thereof and exert a rearward pressing action thereon to effect partial flexure of the extremity away from the stack, and swinging means coming into action
- 5 after the initial flexing and engaging the flexed portion to move the same substantially into a position at right angles to the body thereof, and means coordinated in operation with the swinging member and the swinging means for relieving the pressure of the follower on the flexed article to allow the removal thereof.
21. In a dispensing device, a movable follower for a stack of folded, flexible sheets each having a transverse line of fold forming the forward end thereof, a wall engaging a portion of the stack at the opposite end, a member extending transversely across the exposed surface of the outermost article inwardly from the extremity thereof and movable rearwardly to exert a flexing pressure thereon to effect separation of the exposed portion of the article from the stack, means adapted to engage the flexed portion to further flex the same, and means for relieving the pressure of the follower on the stack to allow the outermost article to be drawn out guided around said transverse member.
22. In a dispensing device, a magazine having a spring pressed follower for supporting a stack of flexible articles, a wall portion overlying a portion of the stack at the opposite end and receiving the thrust of the follower, means adapted to engage the outermost article to flex the same to cause separation of the exposed extremity from the stack, and means controlled by the operation of the flexing means for engaging the follower in each position thereof and slightly retracting the same and locking the same in retracted position to allow removal of the flexed article, said last named means releasing the follower upon actuating of the flexing means.
23. In a dispensing device, a magazine for a stack of flexible articles including a spring pressed follower at one end of the stack, and a wall portion overlying a portion of the opposite end of the stack and receiving the thrust of the follower, means engageable with the outermost article to cause the flexing thereof away from the stack, and means controlled by the flexing means for retracting said follower to allow withdrawal of the flexed article, said retracting means including a detent on the follower and an elongated member having means extending therealong adapted to interlock with the detent in any position of the follower, said member having a combined longitudinal and transverse movement into and out of engagement with said detent to effect the retraction and locking of the follower or the release thereof.
24. The method of dispensing thin flexible articles, which consists in folding the article to produce parallel upper and lower layers united along a line of fold, engaging the top layer with a friction member which presses thereon along a line parallel to the line of fold and, while maintaining such engagement, moving the engaging surface of the friction member in a direction away from the line of fold, whereby the upper layer is caused to pull upon the lower layer and elevate the end which is pulled upon, and in thereupon engaging such elevated end and mov-
- ing it to increase its elevation and to bring it into a position where it may be readily grasped.
25. The method of dispensing thin flexible articles, which consists in folding the article to produce parallel upper and lower layers united along a line of fold, engaging the top layer with a friction member in a region adjacent to the line of fold and, while maintaining such engagement, moving the engaging surface of the friction member in a direction away from the line of fold, whereby the upper layer is caused to pull upon the lower layer and elevate both thereof, and in thereupon engaging such elevated portion and moving it to increase its elevation and to bring it into a position where it may be readily grasped.
26. In a dispensing device, a magazine including a spring operated follower for a stack of folded, flexible sheets each having a transverse line of fold forming the forward end thereof, and a member extending transversely across a forward portion of the uppermost article of the stack, and mounted to swing towards and rearwardly along the uppermost article exerting a pressure thereon to cause the advance portion of the article to flex away from the stack.
27. In a dispensing device, a movable follower for feeding a stack of folded, flexible sheets each having a transverse line of fold forming the forward end thereof, pressing means movable into engagement with the outermost article of the stack and rearwardly thereover for flexing the forward portion of said outermost article away from the stack, and means becoming operative upon the release of said pressing means for retaining said flexed portion in separated relation to the stack and for relieving the pressure of the follower on the flexed article to facilitate the removal thereof.
28. In a dispensing device, a movable follower for feeding a stack of folded sheets, means engageable with the outermost article of the stack for flexing the same, means engageable with said follower to retract and lock the same in any of the feeding positions thereof, and means for actuating said several means, said last named means operating to lock said follower in retracted position when said flexing means is released, and to release said follower when said flexing means is actuated to flex the outermost article.
29. A device as in claim 28 including means moved by said actuating means into engagement with the flexed portion of the article when said flexing means is released therefrom.
30. The method of dispensing folded articles which consists in folding flexible sheets to produce parallel upper and lower layers, the layers of each folded sheet being also folded along an intermediate transverse line of fold forming the forward end of the article, engaging the outermost article of a stack of such articles with a friction member at the rear of the forward end of the article and, while maintaining said engagement, moving the engaging surface of the friction member rearwardly over the face of the article to cause the outer layer to pull upon the lower layers and flex the forward end of the article away from the stack, and releasing the pressure on said outermost article while retaining the flexed end thereof in separated relation to the stack.

CERTIFICATE OF CORRECTION.

Patent No. 1,965,060.

July 3, 1934.

SAMUEL SHAPIRO.

It is hereby certified that error appears in the printed specification of the above numbered patent requiring correction as follows: Page 4, line 1, claim 4, for "first" read second; and that the said Letters Patent should be read with this correction therein that the same may conform to the record of the case in the Patent Office.

Signed and sealed this 11th day of September, A. D. 1934.

(Seal)

Leslie Frazer
Acting Commissioner of Patents.
